UNITED STATES PATENT OFFICE.

MARCEL REDON, OF LIMOGES, FRANCE, ASSIGNOR TO FRANCIS H. BAWO,
AND CHARLES T. DOTTER, OF NEW YORK, N. Y.

DESIGN FOR TABLE-WARE.

SPECIFICATION forming part of Design No. 13,477, dated December 12, 1882.

Application filed November 3, 1882. Term of patent 7 years.

To all whom it may concern:

Be it known that I, MARCEL REDON, residing at Limoges, in the county of Haute Vienne, in the Republic of France, have originated a new Design for Table-Ware, of which the following is a specification.

My design consists in the representation on the body of an article of table-ware of a number of strips of wood arranged side by side.

10 The design also consists in the representation on the body of an article of table-ware of a number of strips of wood bent double and having the ends extending downward.

15 The design also consists in the representation on the body of an article of table-ware of a number of strips of wood stitched together at the upper portion.

20 The design also consists in the representation on the body of an article of table-ware of a number of strips of wood and a cord bound around them near the lower ends.

25 The design also consists in a handle made in the form of a number of sticks of wood bound together by bands.

30 In the accompanying drawings, Figure 1 is a side view of a dish embodying my design. Fig. 2 is a side view of one of the end handles, and Fig. 3 is a top view of the cover-handle. Similar letters of reference designate corresponding parts in all the figures.

35 A designates the body of the dish. Its lower part is embellished with the representation of a number of strips, *a*, of wood, doubled and arranged with their ends downward. These strips in this example of the design are rep-

resented in close contact. The upper bent portions of these strips are represented as connected by stitches *b*, and the lower ends are represented as bound to the dish by a cord, *c*. The end handles, *B*, of the dish are made to 40 represent pieces of wood *e*, laid side by side and bound together by bands *d*. The handle *C* of the cover *D* of the dish is represented as consisting of three pieces, *f*, of wood, united by bands *g*.

45 Other articles of table-ware may be made to embody this design.

What I claim as my design, and desire to secure by Letters Patent, is—

1. The representation on the body of an article of table-ware of a number of strips of wood arranged side by side.

2. The representation on the body of an article of table-ware of a number of strips of wood bent double and having the ends extending 55 downward.

3. The representation on the body of an article of table-ware of a number of strips of wood stitched together at the upper portion.

4. The representation on the body of an article of table-ware of a number of strips of wood and a cord bound around them near the lower ends.

5. A handle made in the form of a number of sticks of wood bound together by bands.

M. REDON.
